CONTAINER FOR MERCHANDISE

Robert R. Lurette, New Orleans, La., assignor of twenty per cent to Vergie Lurette, fourteen per cent to James Leland Cooper, and fifteen per cent to Leo R. Wertheimer, all of New Orleans, La.

Application October 30, 1937, Serial No. 172,007

2 Claims. (Cl. 206—7)

The present invention relates to new and useful improvements in containers and relates more particularly to shipping containers for neckties or other apparel, and has for its primary object to provide, in a manner as hereinafter set forth, a device for displaying neckties on a shelf or counter in a store, that may be folded to form a shipping container for shipping a necktie.

Another object of the invention is to provide a container for supporting a necktie so as to insure its delivery in an unruffled condition.

Another object of the invention is to provide a container for neckties requiring a minimum of space when stored.

15 All of the foregoing and still further objects and advantages of the invention will become apparent from a study of the following specification, taken in connection with the accompanying drawings wherein like characters of reference 20 designate corresponding parts throughout the several views, and wherein:

Figure 1 is a perspective view of my invention.

Figure 2 is a perspective view of the invention in open position.

25 Figure 3 is a view of the invention in blank form.

Referring now to the drawings in detail, it will be seen that the embodiment of the invention which has been illustrated comprises a back portion 5 having a longitudinal slit 6 substantially in its center. A V-shaped tongue 7 is stamped from the back portion 5 near the slit 6.

A necktie carrying portion 8 has transverse slits 9 therein near the ends thereof to provide 35 loops or straps 10 under which the ends of a folded necktie 11 are inserted as shown in Figure 2. The necktie carrying portion 8 is folded, on a scored line 12 over the back portion 5, and tabs 13 on the back portion 5 fold over the ends of the 40 folded necktie 11 and necktie carrying portion 8, to prevent longitudinal displacement of the necktie 11.

A front portion 14 folds over the necktie carrying portion 8 and the tabs 13, along the scored 45 line 15, to cover the necktie 11, necktie carrying portion 8 and the tabs 13.

A flap 16 folds, along a scoring 17, over the back portion 5 and is inserted in the slit 6 and held in position by engagement of the tongue 7 in a slit 50 18 in the flap 16.

When the device is used as a display for the necktie 11, the front portion 14 is bent and folded behind the back portion 5 and the flap 16 is inserted in the slit 6, thus disclosing and displaying 55 the necktie.

When the device is used as a shipping container the necktie 11 is inserted in the necktie carrying portion 8, as shown in Figure 2, and the front portion 14 is folded over the necktie 11 and necktie carrying portion 8. The flap 16 is then inserted in the slit 6 in the back portion. The tongue 7 is engaged in the slit 18 in the flap 16 to hold the same in the slit 6.

Although I have shown and described herein a preferred embodiment of my invention, it is to be definitely understood that I do not desire to limit the application of the invention thereto, and any change or changes may be made in the material and in the structure and arrangement of the parts within the spirit of the invention as claimed.

What is claimed is:

1. In a combined necktie display and retaining device the combination of, a back panel, a necktie-retaining deck panel hingedly connected to one side of said back panel, a cover panel hingedly connected to the opposite side of said back panel and arranged to fold over said deck panel, a retaining flap hingedly connected to the other side of said cover panel and adapted to hold said cover panel in a closed position, the aforesaid deck panel having spaced pairs of slits defining a pair of necktie-retaining straps, said straps being arranged transversely to the longitudinal edges of said deck panel, and freely foldable flaps hingedly connected to the ends of said back panel and arranged to fold over the extremities of a necktie carried by the deck panel and said straps being arranged to embrace and overlie the aprons of the necktie.

2. In a combined necktie display and retaining device the combination of, a back panel, a necktie-retaining deck panel hingedly connected to one side of said back panel, a cover panel hingedly connected to the opposite side of said back panel and arranged to fold over said deck panel, a retaining flap hingedly connected to the other side of said cover panel and adapted to hold said cover panel in a closed position, the aforesaid deck panel having a pair of slits, one being arranged near one end of the deck panel but removed from 35 the end, the other being arranged near the other end of the deck panel but also removed from the end, said slits being adapted to have a necktie threaded therethrough, and freely foldable flaps hingedly connected to the ends of said back panel 40 and arranged to fold over the extremities of a necktie carried by the deck panel and said straps being arranged to embrace and overlie the aprons of the necktie.

3. In a combined necktie display and retaining device the combination of, a back panel, a necktie-retaining deck panel hingedly connected to one side of said back panel, a cover panel hingedly connected to the opposite side of said back panel and arranged to fold over said deck panel, a retaining flap hingedly connected to the other side of said cover panel and adapted to hold said cover panel in a closed position, the aforesaid deck panel having a pair of slits, one being arranged near one end of the deck panel but removed from 45 the end, the other being arranged near the other end of the deck panel but also removed from the end, said slits being adapted to have a necktie threaded therethrough, and freely foldable flaps hingedly connected to the ends of said back panel 50 and arranged to fold over the extremities of a necktie carried by the deck panel and said straps being arranged to embrace and overlie the aprons of the necktie.
